United States Patent Office

Des. 194,765
Patented Mar. 5, 1963

194,765

ROTARY-WING AIRCRAFT

Lyle K. V. Sudrow, Los Angeles, Calif., assignor to
Helpod, Inc., Oceanside, Calif., a corporation of Calif-
ornia

Filed July 18, 1961, Ser. No. 65,966

Term of patent 14 years

(Cl. D71—1)

Fig. 1

Fig. 4

FIGURE 1 is a perspective view of a rotary-wing aircraft, embodying my new design;

FIGURE 2 is a side elevation thereof;

FIGURE 3 is a front elevation thereof; and

FIGURE 4 is a top plan view.

The side opposite that shown in FIGURE 2 is a mirror image thereof, except for the door opening and handle below the window line.

I claim:

The ornamental design for a rotary-wing aircraft, substantially as shown and described.
